(57) **CLAIM**

The ornamental design for an auxiliary frame for curtain cutting, as shown and described.

DESCRIPTION

FIG. 1 is a perspective view of an auxiliary frame for curtain cutting, showing our new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The evenly broken lines shown in the drawings depict portions of the auxiliary frame for curtain cutting in which the design is embodied that form no part of the claimed design.
